FINIAL FOR LAMPS OR SIMILAR ARTICLES

John M. Black, Chicago, Ill., assignor to Commonwealth Plastics, Inc., Chicago, Ill., a corporation of Delaware

Application February 20, 1951, Serial No. 14,283

Term of patent 14 years

(Cl. D48—7)

To all whom it may concern:

Be it known, that I, John M. Black, a citizen of the United States, residing at Chicago, in the county of Cook and State of Illinois, have invented a new, original, and ornamental Design for a Finial for Lamps or Similar Articles, of which the following is a specification, reference being had to the accompanying drawing, forming part thereof, in which:

Fig. 1 is a top plan view of a finial for lamps or similar articles, showing my new design.

Fig. 2 is a side elevational view thereof; and
Fig. 3 is a cross sectional view taken on the line
3—3 of Fig. 2.

I claim:

The ornamental design for a finial for lamps or similar articles, as shown.

JOHN M. BLACK.
